UNITED STATES PATENT OFFICE.

JOHN E. STENBERG, OF CHICAGO, ILLINOIS.

DESIGN FOR A STAND.

44,989.

Specification for Design.

Patented Dec. 2, 1913.

Application filed October 22, 1913. Serial No. 796,740. Term of patent 7 years.

To all whom it may concern:

Be it known that I, JOHN E. STENBERG, a citizen of the United States, residing at Chicago, in the county of Cook and State of Illinois, have invented a new, original, and ornamental Design for Stands, of which the following is a specification, reference being had to the accompanying drawing, forming a part thereof.

Figure 1 is a side elevation, and Fig. 2 an

under side view of a stand, showing my new design.

I claim:

The ornamental design for a stand, as shown.

JOHN E. STENBERG.

Witnesses:

C. PAUL PARKER,
GEORGE L. CHINDAHL.
